UNITED STATES PATENT OFFICE.

FRANK W. ROBISON, OF DOLTON, ILLINOIS.

SANITARY CHALK-THROUGH SCREEN.

1,097,468.

Specification of Letters Patent. Patented May 19, 1914.

Application filed June 3, 1913. Serial No. 771,538.

To all whom it may concern:

Be it known that I, FRANK W. ROBISON, a citizen of the United States, residing at Dolton, in the county of Cook and State of Illinois, have invented new and useful Improvements in Sanitary Chalk - Trough Screens, of which the following is a specification.

This invention relates to chalk trough screens the object in view being to provide a sanitary screen for the chalk troughs used in connection with blackboards for catching the chalk dust falling from the board and from the brush used for cleaning off the board.

The principal aim of the present invention is to produce a simple, cheap and effective screen for the purpose stated, combined with novel means for fastening said screen to the chalk trough, to enable the screen to be turned over from its normal position to a hanging or pending position at the front edge of the trough during the operation of moving the accumulated chalk dust from the trough.

With the above and other objects in view, the invention consists in the construction, combination and arrangement of parts, as will hereinafter be more fully described, illustrated and claimed.

In the accompanying drawings:—Figure 1 is a perspective view of a portion of a blackboard and chalk trough, showing the screen of this invention applied thereto and in its operative position. Fig. 2 is a similar view showing the screen thrown back to its pendent position. Fig. 3 is an enlarged detail view of one of the devices for fastening the screen to the trough.

Referring to the drawings 1 designates a blackboard, 2 a chalk trough secured to the bottom thereof and extending outwardly therefrom and 3 the screen of this invention.

The body of the screen 3 is formed preferably of galvanized or japanned mesh wire fabric as indicated at 4 and in carrying out this invention, said screen is provided along one of its longitudinal edges with a laterally bent portion or flange 5, which, when the screen is in its operative position stands upwardly from the outer edge of the body of the screen as shown in Fig. 1.

Extending along the marginal edge of the upturned flange 5 is a wire 6 considerably heavier than the wire of which the body of

the screen is formed, the wire 6 serving to reinforce the upturned edge of the screen and also acting as a hinge pin as will hereinafter appear.

In connection with the screen, any desired number of fastening devices are employed, one of said fastening devices being illustrated in detail in Fig. 3 wherein it will be observed that said fastening device resembles somewhat a screw-eye in that it comprises a threaded shank 7 and an eye portion 8 formed integrally with the shank. The fastening device shown in Fig. 3 differs, however, from the ordinary screw-eye in that it is provided with a downwardly offset portion 9 forming a drop step in which the wire 6 above referred to seats itself when the screen is in its operative position. This prevents the wire 6 from moving about loosely in the eye 8, the wire 6 being held in the steps 9 of the several fastening devices which fastening devices are screwed into the outer edge portion of the trough 2 as indicated in Figs. 1 and 2. By reason of the particular shape of the wire screen, that is to say, by reason of the upturned flange 5, combined in the manner set forth with each fastening device, the screen may be turned over from the position illustrated in Fig. 1 to the position illustrated in Fig. 2, said flange permitting the main body portion of the screen to hang pendent from the outer edge of the trough as shown in Fig. 1, the inner and outer edges thereof resting directly on the corresponding portions of the trough and thereby preventing the chalk dust from finding its way outwardly between the screen and the edges of the trough. In other words the construction described insures a close contact between the screen and the upstanding edge portions or flanges 10 of the trough.

What is claimed is:—

1. The combination with a chalk trough, of fastening devices secured to the outer edge of the trough and provided with eyes, and a screen normally resting on the outer and inner edges of the trough and provided along its outer edge with an upstanding flange, the upper edge of which passes through the eyes of the fastening device.

2. The combination with a chalk trough, of fastening devices secured along the outer edge thereof, and a screen normally resting on the inner and outer edges of the trough and embodying an upstanding flange along

its outer edge, and a hinge wire extending along the upper edge of said flange and passing through said fastening devices, where-
5 by the screen is hinged to the trough and adapted to be turned from its operative to a pendent position, substantially as de-
scribed.

In testimony whereof I affix my signature in presence of two witnesses.

FRANK W. ROBISON.
